UNITED STATES PATENT OFFICE.

RALPH B. SMITH, OF LAWRENCE, MASSACHUSETTS, ASSIGNOR TO RALPH B. SMITH AND JOHN W. SMITH, BOTH OF LAWRENCE, MASSACHUSETTS, COPARTNERS, DOING BUSINESS UNDER THE FIRM-NAME OF WILLIAM SMITH & SONS.

BALING-PRESS FOR HANK-YARN.

1,281,254.

Specification of Letters Patent.

Patented Oct. 8, 1918.

Application filed March 28, 1918. Serial No. 225,217.

To all whom it may concern:

Be it known that I, RALPH B. SMITH, a citizen of the United States, residing at Lawrence, in the county of Essex and State 5 of Massachusetts, have invented certain new and useful Improvements in Baling-Presses for Hank-Yarn; and I do hereby declare the following to be a full, clear, and exact description of the invention, such as will enable others skilled in the art to which it 10 appertains to make and use the same.

The present invention relates to an improvement in baling presses. The object of the invention is to produce a simple and inexpensive 15 baling press for use in baling wool in hanks, and one which has various features of construction hereinafter referred to, which conduce to the efficiency and rapidity with which it may be operated. 20 To the above ends, the present invention consists in the baling press described in the following specification and particularly defined in the claims.

In the accompanying drawings illustrating 25 the preferred form of the invention, Figure 1 is a side elevation of the baling press, and Fig. 2 is an end elevation of the same with the standard removed.

The illustrated embodiment of the invention 30 is described as follows:

The baling press is provided with a base 1 which supports a standard 2 which comprises a hydraulic or pneumatic actuating cylinder. This cylinder 2 is flanged at its 35 upper end at 3 and has secured to this flange a bed-plate 4. Mounted on each end of the bed-plate are hank-pins 5 which are received in the hank-pin brackets 6 which are secured by screws 7 to the ends of the bed-plate 4. 40 Bosses 8 on the bracket 6 have holes which receive the hank-pins 5, being secured in the holes by means of the set screws 9. On the front and back of the bed-plate 4 are secured side guides 10 and 11, 10 being guides provided with locking devices and 11 being plain guides. Four rear guides 12 correspond to the four front guides 10, and each rear guide 12 is provided with a swinging cover 13 pivoted at 14 to the upper end of 45 the rear guides 12. A rearward extension 15 of the top of the covers 13 is provided to support the covers 13 in open position as shown in dotted lines in Fig. 2. The front

guides 10 are each provided with a lock lever 16 which is pivoted at 17 to the side of the guide 10. This lock lever 16 has a little projection on its lower end which is adapted to engage the guide 10 and hold it in its open position as shown in dotted lines in Fig. 2. The upper end of the lever 16 is received in a slot in the front end of the cover 13. When the cover is closed and the lever 16 is moved to the full line position shown in Fig. 2, the handle-collar 18 of the lever slips over a little prominence 19 on the end 55 of the cover 13 so as to be held thereby from slipping off. The platen 20 of the press is a rectangular plate supported at its center by the plunger rod 21 which carries upon its lower end the piston 22 which is received in 60 the cylinder 2. The plunger rod 21 is packed where it passes through the bed-plate 4 by means of a gland 23. A pressure pipe 24 connects with the lower end of the cylinder 2; a pressure pipe 25 connects with the upper end of the cylinder 2. These in turn are connected with the four-way valve 26 which is provided with a handle 27 by which it is operated so as to connect the supply pipe 25 with the exhaust pipe 29, or vice versa, to 70 connect the supply pipe 28 with the top pipe 25 and the exhaust pipe 29 with the bottom pipe 24. 75

In baling hanks of yarn, one end of the hank is looped over a hank-pin 5 at one end 85 of the press, then the hank is twisted more or less and the other end of the hank is looped over the opposite pin 5 at the other end of the press. Hanks are set up on the pins from the platen 20 to the top of the 90 press, and they are forced down by hand pressure until as many hanks as are desired to be baled together are arranged in position; then the covers 13 are turned down over the hanks and the locking lever 16 95 thrown into position to hold the covers in place. Thereupon the four-way valve is operated to admit pressure to the bottom of the cylinder 2, which thereby forces the piston upward, causes the platen 20 to rise and to compress the hanks of yarn to the desired degree, when strings, previously placed on the platen, will be tied around the yarn. The pressure will be relieved by turning the 100 four-way valve so as to connect the lower 105 end of the cylinder with the exhaust, where-

upon the press will be opened by unlocking the covers, and the bale will be lifted out. Compressed air, or water, or oil under pressure, may be used to operate the press. The 5 press is readily loaded with hanks of yarn, the closure of the cover is easily and quickly effected, pressure promptly and effectively applied without excessive labor on the part of the operator, and the baling of the hanks 10 is completed by tying the compressed body of hanks while under pressure.

Having thus described the invention, what is claimed is:—

1. A baling press for hank-yarn having, 15 in combination, a bed-plate, a plurality of guides secured to the bed plate on its sides and ends, the end guides constituting supports for the yarn hanks and the side guides constituting side supports to prevent lateral 20 displacement of the yarn, a cover and a platen, and means for actuating the platen to press the hanks supported on the platen and between the guides.

2. A baling press having, in combination, 25 a platen, a vertical guide supported on one side of the platen provided with a locking lever; a guide supported on the other side of the platen provided with a cover secured

thereto and adapted to be locked in closed position by the locking lever. 30

3. A baling press having, in combination, a bed plate, a platen, a series of hank pins at each end of the bed-plate adapted to receive a plurality of yarn hanks, a cover, and pressing means. 35

4. A baling press for hank-yarn having, in combination, a base, a standard consisting of a pressure cylinder, a bed-plate mounted on the upper end of the cylinder, a guide secured to the bed-plate, a piston in 40 the cylinder, a platen above the bed-plate, a plunger rod connecting the piston with the platen, guides for the yarn, and a cover and locking means therefor.

5. A baling press for hank-yarn having, 45 in combination, a bed-plate, a plurality of guides secured to the bed-plate at its sides and ends, the end guides constituting supports for the yarn hanks, and the side guides constituting side supports to prevent lateral 50 displacement of the yarn, alternate members of the side guides being provided with covers and locking means, a platen and actuating means therefor.

RALPH B. SMITH.
